United States Patent Office

Des. 181,852
Patented Jan. 7, 1958

181,852

VEHICLE SEAT OR SIMILAR ARTICLE

Elmer A. Herider, Dearborn Township, Mich., assignor
to Rockwell Spring and Axle Company, Coraopolis,
Pa., a corporation of Pennsylvania

Application October 3, 1955, Serial No. 38,205

Term of patent 14 years

(Cl. D15—8)

Figure 1 is a front perspective view of a vehicle seat or similar article, showing my new design;

Figure 2 is a fragmentary side elevational view thereof; and

Figure 3 is a rear perspective view thereof to a reduced scale.

The dominant features of my new design are shown by means of solid lines in the drawing.

I claim:

The ornamental design for a vehicle seat or similar article, as shown and described.
